UNITED STATES PATENT OFFICE.

LOUIS LOWENSTEIN, OF BROOKLYN, NEW YORK, ASSIGNOR TO JOHN P. MANN, HARRY MORRIS, AND FRANK O. REILLY, COPARTNERS DOING BUSINESS UNDER THE FIRM-NAME OF MORRIS, MANN & REILLY.

LADY'S VANITY-BAG.

1,181,080.

Specification of Letters Patent. Patented Apr. 25, 1916.

Application filed October 1, 1913. Serial No. 792,725.

To all whom it may concern:

Be it known that I, LOUIS LOWENSTEIN, a citizen of the United States, residing at 1956 Eighty-fifth street, in the city of Brooklyn, Kings county, New York, have invented new and useful Improvements in Ladies' Vanity-Bags, of which the following is a specification.

This invention relates to ladies' vanity bags or hand bags and similar devices and has for one of its objects the providing of a suitable and artistic device which will be strong and durable in construction and inexpensive to manufacture. Such a device is illustrated in the accompanying drawings in which:

Figure 1 is a view of the device in perspective. Fig. 2 is a horizontal section on the line 2 of Fig. 1. Fig. 3 is a vertical section on the line 3 of Fig. 1.

As shown in said drawings the device consists of a flat and rectangular piece of material 10 having pockets on both sides which are covered by folding flaps. The part 10 consists of two layers or plies of cloth or other suitable material 11 which are stiffened by a ply of paste-board or similar material 12 between them. The covering flaps are indicated at 16, 17, 18 and 19 respectively and they are preferably constructed of a layer of thin leather or other suitable material 20 with a lining of cloth 21, as indicated in Fig. 3 showing two of the flaps in cross section. On one side of the central member 10, at its lower part, is provided a small pocket 24 having a covering flap 25 which buttons down over it; and above it is placed a mirror 26; and both of these are covered by the two flaps 16 and 17, the former being folded up, and the latter down over it and buttoned to it by means of a snap button 29. A pocket is also provided in the flap 16 by joining its lining to it on three sides only, leaving a slit 30 along one edge for the insertion of a memorandum card or note book 33. On the opposite side of the central member 10 are the two overlapping flaps 18 and 19, and the lower one 18 besides

being joined to the part 10 along its lower edge is also connected thereto along its two vertical edges by triangular bellows strips 38 so as to provide a pocket beneath it for the insertion of small articles; and this pocket is covered by the overlapping flap 19 on which is fixed a snap button 41 to engage in a corresponding socket on the flap 18, not here shown.

The device above described, comprising the central member 10 with the four folding flaps, two of which are joined to it along its top edge and two along its bottom edge, is made by arranging these parts in the manner described and joining their edges together by means of a continuous rectangular metal rim 40 which is of channel section and is pinched together over the four edges of the part 10 and the attached edges of the folding flaps and of the pocket 24 and the pieces 38, so as to secure all these parts together and stiffen and strengthen the entire device; and also receive the wear which is always greatest at the corners and edges of such a device. To the rim 40 may also be joined the ends of a handle or looped chain 45 for carrying the device. 75

I claim as my invention:

A bag formed of several plies of flexible material, one of them being a center member and others being joined to it along its bottom and side margins to form pockets on both sides of such center member, other plies of flexible material joined to the margins of such center member and forming flaps to cover such pockets, and a continuous metal rim of channel section embracing the edges of such center member and the attached edges of such flaps and pockets to secure such parts together and strengthen and stiffen the entire device. 85

In witness whereof, I have hereunto subscribed my name in the presence of two witnesses this 26th day of September, 1913.

LOUIS LOWENSTEIN.
